(57) **CLAIM**

The ornamental design for a container with container lid, as
shown and described.

DESCRIPTION

FIG. 1 is a perspective view of a container with container lid
in an assembled position as seen from the top, front and first
sides, showing our new design;

FIG. 2 is a perspective view of the container with the
container lid shown in an assembled and closed position as
seen from the bottom, rear and second sides thereof;

FIG. 3 is a front elevational view thereof;

FIG. 4 is a rear elevational view thereof;

FIG. 5 is a first side elevational view thereof;

FIG. 6 is a second side elevational view thereof;

FIG. 7 is a top plan view thereof;

FIG. 8 is a bottom plan view thereof;

FIG. 9 is a perspective view of the container with the
container lid shown in a disassembled position as seen from
the top, front and first sides;

FIG. 10 is a perspective view of the container with the
container lid shown in a disassembled position as seen from
the bottom, rear and second sides;

FIG. 11 is a front elevational view thereof;

FIG. 12 is a rear elevational view thereof;

FIG. 13 is a first side elevational view thereof;

FIG. 14 is a second side elevational view thereof;

FIG. 15 is a perspective view of the container lid as seen
from the top, front and first sides;

FIG. 16 is a perspective view of the container lid as seen
from the bottom, rear and second sides;

FIG. 17 is a front elevational view thereof;

FIG. 18 is a rear elevational view thereof;

FIG. 19 is a second side elevational view thereof;

FIG. 20 is a first side elevational view thereof;

FIG. 21 is a top plan view thereof; and,

FIG. 22 is a bottom plan view thereof.

(Continued)

The broken lines in the drawings depict portions of the container with container lid that form no part of the claimed design.
